UNITED STATES PATENT OFFICE.

OTTO STÜTTGEN, OF FUTERBOG, GERMANY.

DEVICE FOR STRETCHING WIRE AND WIRE ROPES.

Application filed March 31, 1921. Serial No. 457,549.

To all whom it may concern:

Be it known that I, OTTO STÜTTGEN, a citizen of the German Republic, residing at Futerbog, in the State of Prussia, Germany,

5 have invented certain new and useful Improvements in Devices for Stretching Wire and Wire Ropes (for which I have filed applications in Germany November 30, 1918, D. R. P. No. 318,536, and May 11, 1919, D. 10 R. P. No. 325,060), of which the following is a specification.

This invention relates to devices for stretching wire and wire ropes, of the type in which on a guiding-rod, which at one

15 end carries a hook for its suspension from a fixed point, for instance a pole, a pair of clamping-jaws, which serve for pulling and which close automatically, are slidably arranged by means of a lever-gearing, while 20 a second pair of clamping-jaws, which are immovably located between said suspension hook and said first pulling pair and which close also automatically, hold the stretched wire fast during the time in which said 25 first pulling pair are disengaged from the wire and are, by means of the lever-gearing, again applied thereto at a point toward the front.

With the known arrangements of this 30 type, the wire to be stretched is held fast by camlike pairs of clamping-jaws and is thus liable to be damaged, when stretched, owing to the strong pressure of the comparatively short clamping surfaces.

35 With the arrangement of the present invention, instead of the camlike clamping-jaws, so called parallel clamping jaws are used, by which damage to the wire can be avoided. Such parallel clamping-jaws, per 40 se alone, are already used heretofore for stretching wires, as a substitute for the known devil's claws or Dutch tongs with camlike jaws used for the same purpose, and that in connection with pulley-blocks, by 45 which the stretching of the wire takes place, the clamping-jaws being here applied to the wire mostly once only, or, if several times, at large intervals only. With said known parallel jaws, however, a universal step-by- 50 step stretching work, by which the jaws, so-to-say, climb along the wire and catch the same again and again at short intervals, cannot be performed.

The essence of the present invention consists, mainly, in the combination of a lever wire-stretcher with a parallel clamping

claw, so that on the one hand a step-by-step work can be performed and on the other hand, contrary to the hitherto used devices, the wire is prevented from being damaged 60 when stretched. Thus, it is possible with the improved device to stretch also wires covered with silk or other sensitive material.

Furthermore, with the hitherto used lever wire-stretchers, it is difficult to free the 65 readily stretched wire, that is still clamped fast with the ends engaged, from the holding-claw of such lever wire-stretchers, owing to the grip of the clamping-jaws being maintained by the pull of the wire.

70 To meet this inconvenience, according to the present invention, at the point of attachment of the lever-gearing of the pulling-claw, a turnable abutment-arm is located and made of a length practically equal to 75 the distance between the pulling-claw in its drawn-out position and the holding-claw, said turnable abutment-arm being turned outwards when stretching the wire.

In order to detach the lever wire-stretcher 80 from the stretched wire, the abutment-arm is turned inwards at the moment when the pulling-claw assumes the position required for pulling the wire, i. e. is advanced for attracting the wire. Thereby, the lever-gearing receives a rest or support on the 85 lower edges of a slide of the holding-claw, on which the clamping-jaws, which are clamped fast on the wire by the pull of the same, are movably arranged. Upon the 90 lever-gearing, and thus also the pulling-claw, being then moved, the jaws of the holding-claw are lifted from the stretched wire.

If such a turnable abutment-arm would be 90 used in connection with lever wire-stretchers having camlike jaws, said abutment-arm must first loosen the jaws clamped fast on the wire before the removal of the jaws becomes possible; consequently, with sensitive 100 wires, this might easily result in a further damage to the latter.

The accompanying drawing represents a plan view of the improved device.

105 *y* is the guiding-rod having at one end a handle *i* and at the other end a suspension-hook *d*. Directly adjacent to said handle, the pulling-claw *b* is arranged. Said claw has parallelly acting clamping-jaws *c*, which are connected by pins *l* to links *m*, the latter 110 being mounted by said pins on a slide *o*, which is movably located on said guiding-

rod. Said links *m* are further pivoted to links *p* connected by bolts *q* to a slide *r*, which is also movably located on said guiding-rod. *e* is a coil-screw intervening between said slides *o* and *r* and tending to compress the jaws *c*. The opening of said jaws *c*, for an insertion and removal of the wire, is effected by the shearlike lever-connection *f* forming extensions on one side of the links 10 *m* and *p* and which remove said jaws from one another until the latter strike on the rear against stops *g* on the slide *o*, the jaws being thus always automatically adjusted in parallel position to the pulling direction. 15 *h h* are the known overthrow-members preventing the wire, while being stretched, from slipping out of said jaws.

The holding-claw *a* located between said pulling-claw *b* afore-described and the hand-lever *u*, is constructed identically like the pulling-claw *b*, with the distinction, however, that, while the slide *r* of the latter is movable on the guiding-rod *y*, the holding-claw *a* has a fixed socket *s* on said guiding-rod, which carries the pivot for said hand-lever *u*.

k is the turnable abutment-arm, the same being mounted on the slide *r* and on the drawing-rod *t* of the hand-lever *u* respectively. Said abutment-arm has a length practically equal to the distance between the slide *r* of the pulling-claw *b* and the lower edge of the slide *o* of the holding-claw *a*, when the pulling-claw *b* is drawn-out by 30 means of the hand-lever gearing *u*, *t*. Upon the abutment-arm *k* being turned to the right for 90°, to the position shown, the slide *r*, which is connected with the drawing-rod *t* and the hand-lever *u* respectively, bears 35 upon the slide *o* of the holding-claw *a* and 40

effects, by operation of said hand-lever *u*, an opening of the clamping-jaws of the holding-claw *a*. Thus, upon stretching of the wire by means of the lever wire-stretcher described being finished and the wire stretched 45 lying clamped fast within the jaws *c* of the holding-claw *a*, the latter can be easily opened by a pressure on the hand-lever *u*, provided that the abutment-arm *k* is adjusted in parallel position to the guiding-rod 50 *y*. By operation of the lever-gearing *u*, *t*, the abutment-arm *k* is pressed, by the drawing-rod *t* and the slide *r*, upwards toward the slide *o* of the holding-claw *a*, said slide moving thereby upwards and turning, by means 55 of the pins *n*, the links *m*, so that the latter lift the jaws *c* of the holding-claw *a*.

I claim:—

A device for stretching wire and wire ropes comprising in combination, a guiding 60 rod, a suspension hook at one end of said guiding rod, an automatically closing pulling claw on said guiding rod, a lever gearing for moving said pulling claw on said guiding rod, an automatically closing holding claw 65 attached to said guiding rod and located between said suspension hook and said pulling claw and adapted to act as soon as said pulling claw is displaced for a further action, and a pair of parallel acting clamping jaws 70 on said pulling claw as well as on said holding claw, substantially as and for the purpose set forth.

In testimony whereof I affix my signature in presence of two witnesses.

OTTO STÜTTGEN.
